DESIGN FOR A SHOE SHAPING DEVICE

Felix De Vito, Brooklyn, N. Y.

Application November 5, 1947, Serial No. 142,318

Term of patent 14 years

(Cl. D7—2)

To all whom it may concern:

Be it known that I, Felix De Vito, a citizen of the United States, residing at Brooklyn, in the county of Kings and State of New York, have invented a new, original, and ornamental Design for a Shoe Shaping Device, of which the following is a specification, reference being had to the accompanying drawing, forming part thereof.

Fig. 1 is a front elevational view of a shoe shaping device, showing my new design;

Fig. 2 is a plan view of the same; and

Fig. 3 is a rear elevational view of the same.

I claim:

The ornamental design for a shoe shaping device, as shown.

FELIX DE VITO.
